UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY.

ARRANGEMENT FOR SUPPRESSING IDLE CURRENT IN RADIOTRANSMITTERS.

Application filed April 6, 1925, Serial No. 20,929, and in Germany April 10, 1924.

My invention relates broadly to apparatus for modulated wave transmission and more specifically to radio telephony transmitters.

An object of the invention is to provide a radio telephony transmitter in which the carrier wave is suppressed both when speech is being transmitted and when speech is not being transmitted.

Other objects will be apparent from the following specification and claims when considered with the accompanying drawing which diagrammatically illustrates the best embodiment of my invention known to me at the present time.

When modulating high frequency oscillations by acoustic oscillations, for the purposes of telephony, it is well known that in the transmitting station generally three frequencies are produced. They are the carrier wave, and the two side bands, one side band having a frequency equal to the carrier frequency plus speech frequency and the other side band having a frequency equal to the carrier frequency minus the speech frequency. The carrier frequency, which alone is being radiated during the speech intervals, has been called the "idle current". This current when not used for the transmission of modulating waves, is often found to be of great disturbance, particularly so in telephony reception by superposition, that is, beat reception. On account of the presence of the carrier of high frequency, the entire frequency band required by the transmitter becomes furthermore unduly wide. It has therefore been suggested to work with the carrier wave suppressed, and for this object certain differential connections of senders have been proposed. It has been found, however, that such arrangements are attended with various technical difficulties.

Now, the present invention furnishes means of a simple nature whereby the undesirable idle current can be removed from the aerial or transmitting circuit. According to the invention an additional circuit is coupled with the high frequency generator and the aerial or transmitting circuit, which is so untuned with relation of the carrier wave, and whose coupling with the generator and the aerial is so adjusted that compensation or neutralization of the carrier frequency is realized in the transmitting circuit.

Referring to the drawing, I and II denote three-element electron discharge tubes of

the audion type, each tube comprising an anode, a filamentary cathode and a control grid all sealed within an evacuated envelope. The cathodes are rendered incandescent by A-batteries and the anode currents are supplied by B-batteries. In order to simplify the drawing neither the A-batteries nor the B-batteries have been shown.

The speech frequency to be transmitted is applied at terminals 1 and 2. The transformer 3 conveys the speech potential to the grid and filament of modulator tube I. The modulator tube I is positioned in series with the grid and filament of oscillator tube II and operates to vary the potential of the grid of tube II according to the speech frequencies.

Oscillator tube II is connected in any well-known manner to generate sustained oscillations. The arrangement shown in the drawing for producing sustained oscillations comprises an inductance coil 14 having a portion 4 thereof arranged in the anode-cathode circuit. The remaining portion 5 of the inductance 14 and a condenser 6 are arranged in 80 the grid-cathode circuit. The output circuit is denoted by III and comprises an inductance 7 and a variable condenser 8 connected to form a closed circuit with the inductance 14. The antenna circuit is denoted by V 85 and has in it an inductance 9 which is coupled to the inductance 7 by means of which coupling energy is transferred from the output circuit III to the antenna circuit V. According to the invention, the antenna circuit 90 V also has in it an inductance 10 to which is coupled by means of an inductance 11 a neutralizing circuit IV. This circuit IV contains a variable condenser 13 for a purpose hereinafter described more in detail, 95 and an inductance 12 which is coupled to the inductance 14.

The operation of this arrangement is as follows: The tube II being connected to act as an oscillation generator will cause a current to flow in output circuit III of the desired carrier frequency when no modulating potential is applied to modulator tube I. During telephony the amplitude of this carrier frequency is controlled in any well-known manner by the speech frequencies through the agency of the modulator tube I. Since a modulated carrier frequency may be decomposed into the carrier frequency and side band frequencies, three frequencies will

then be present in circuit III and will be transferred into the antenna circuit V by means of inductances 7 and 9, and into the neutralizing circuit IV by means of inductances 12 and 14. Condenser 13, however, may be so adjusted that only for energy at the carrier frequency will the phase relation be such that the carrier frequency energy will be neutralized or partially neutralized in the antenna circuit V. For frequencies other than the carrier frequency the phase relations of the voltages induced in antenna circuit V will be such that they will not be neutralized to any appreciable extent.

15 After the proper adjustment of phase and amplitude, the antenna circuit V may be said to be uncoupled to the oscillator tube II with respect to the idle or carrier current. It is necessary that the circuit IV should have as little damping as possible in order that the modulated wave may not be destroyed simultaneously with the suppression of the carrier wave. If the circuit is subject to but little damping, for frequencies for 20 which the condition of uncoupling is not satisfied, there happens a marked variation in the phase, and these oscillations will be radiated with sufficient intensity.

It is a good plan not to uncouple completely, that is, to choose an arrangement such that when no speech modulation takes place, a small current, say 10—20% of the maximum current, will flow in the aerial. When the transmitting apparatus becomes 30 subject to the influence of acoustic modulations (oscillations), there will occur an increase in the current.

I find that it is satisfactory to tune the aerial circuit V, instead of to the carrier frequency, to the frequency of a side band; for example, the aerial circuit might be untuned with reference to the carrier frequency generating circuit by, say, from 1000 to 2000 40 cycles.

45 Having described one embodiment of my invention, I claim:

1. In combination, a source of a carrier wave of relatively high frequency, means for modulating said carrier wave at a relatively low frequency resulting in waves of carrier and side-band frequencies, an antenna circuit, means coupling said antenna circuit to said source, and means permitting the transmission of a wave of said side-band 50 frequency and suppressing a wave of said

carrier frequency comprising a tuned circuit coupled to said antenna circuit and to said source independently of the aforesaid coupling means.

2. In combination, means for producing 60 a carrier wave, means for modulating said carrier wave at an audible frequency, an output circuit, a transmitting circuit coupled to said output circuit, a neutralizing circuit coupled to said transmitting circuit and to 65 said output circuit in such manner that the transmitting circuit is substantially uncoupled from said output circuit with respect to energy at the frequency of the carrier wave.

70 3. In combination, an oscillation generator comprising an electron discharge tube with its grid and anode circuits coupled by an inductance for the production of a carrier wave, means for modulating said carrier wave at an audible frequency resulting in side-band and carrier frequencies, an output circuit which includes the inductance of said oscillation generator, a neutralizing circuit of adjustable impedance coupled to said 75 inductance, a transmission circuit coupled to said output circuit and to said neutralizing circuit, and means to adjust the impedance of said neutralizing circuit whereby energy at said side-band frequencies may 80 be transmitted without appreciable attenuation, while the carrier frequency energy may be suppressed.

4. In combination, a source of modulated carrier frequency energy, an antenna system, means to transfer from the source to the antenna system energy at the carrier and side band frequencies, and means to transfer from the source to the antenna system energy at the carrier frequency and of 90 such phase relation that it will tend to neutralize the carrier wave energy in the antenna system.

5. In combination, a source of modulated carrier frequency energy, an antenna system 100 tuned approximately to a side band frequency, means to transfer from the source to the antenna system energy at the carrier and side band frequencies, and means to transfer from the source to the antenna system energy at the carrier frequency and of 105 such phase relation that it will tend to neutralize the carrier wave energy in the antenna system.

ALEXANDER MEISSNER.
